UNITED STATES PATENT OFFICE.

JOHN LATHROP GRAY, OF ELIZABETH, NEW JERSEY.

DISTILLING AND CRACKING PETROLEUM.

Application filed October 25, 1918. Serial No. 259,649.

To all whom it may concern:

Be it known that I, JOHN LATHROP GRAY, a citizen of the United States, residing at Elizabeth, in the county of Union, State of

6 New Jersey, have invented certain new and useful Improvements in Distilling and Cracking Petroleum; and I do hereby declare the following to be a full, clear, and exact description of the invention, such as 10 will enable others skilled in the art to which it appertains to make and use the same.

This invention relates to certain new and useful improvements in the distillation and cracking of crude petroleum, and is particularly designed to permit the continuous distillation of heavy residuals and crude oils to coke at a relatively low cost, both with respect to the initial expense of the installation and the efficiency and economy of maintaining and operating it.

The invention is particularly applicable to the treatment of Mexican crude oil or like crude oil containing relatively large proportions of sulfur, inasmuch as the process 25 involves the obtaining of a product whereof the sulfur content is reduced to the low minimum tolerated for use in a fuel oil in the firing of marine boilers and the like. By the practice of the process it is possible to 30 obtain in a single and continuous operation from these crude oils, heavily charged with sulfur, a correspondingly refined distillate, and a residual coke having a fuel value which largely contributes to the industrial 35 and economical availability of the process for widely extended use.

The nature and scope of the invention will be more fully understood by reference to the accompanying drawings, which illustrate a 40 form of apparatus adapted for its successful practice.

In the drawings.—

Fig. 1 represents a longitudinal vertical section of the apparatus, partly in elevation;

45 Fig. 2 represents a horizontal section thereof taken on a plane indicated by the line 2—2 of Fig. 1;

Fig. 3 represents a vertical section taken on a plane indicated by the line 3—3 of 50 Fig. 1.

Fig. 4 represents in perspective, the piping system for the supply of the oil to the individual members of the distilling unit

and certain auxiliary heating and cooling devices incident to the practice of the invention;

55 Fig. 5 represents on a larger scale, a sectional elevation of the lower portion of one of the distilling elements with its oil supplying and cooling devices.

60 Similar numerals of reference indicate similar parts throughout the several views.

Referring to the drawings, 4 indicates a furnace chamber provided with any suitable form of fire-box and ash pit 5, for the 65 maintenance of a sufficient heat for the distilling and cracking operation. A furnace stack 6 provided with a regulating damper 7 controls the furnace draft and permits the operator to establish and maintain the 70 necessary heating conditions. It will, of course, be understood that the particular furnace illustrated is but typical of many others that might be employed for the same purpose; that is to say, to heat the distilling 75 and cracking apparatus now to be described.

The distilling and cracking apparatus consists of a unit which, in the particular embodiment shown in the drawing, is made up of a series of upright tubes 8, united at 80 the top by a common header 9. This header discharges by an elbow pipe 10 into an upright drum 11 which serves as a receptacle for the coke produced as a residuum in the process and also as a collecting and transmitting drum for the gaseous or vaporous products of the distillation on their way to the condenser. The still and also the condenser may, if desired, be maintained under pressure so as to assist in the cracking of the 90 vapors and their liquefaction.

The main or leading characteristic of the invention consists in the employment within the upright tubes 8 of a filling, adapted to become liquid upon the application of 95 heat, and through which the crude oil or the like to be distilled and coked is caused to pass. The filling preferred for this purpose is lead, or its equivalent, introduced in a molten state into the individual pipes 8 100 through suitable pouring openings in the header at points immediately above the upper ends of the tubes, which openings are adapted to be thereafter closed by means of screw plugs 12 or the like.

105 The lower end-cap 30 of each individual

2
tube 8 is adapted to rest within a base plate 31, and each tube is provided with a plug 13 shown in detail in Fig. 5. The upper screw-threaded end 14 of this plug engages a corresponding interior screw thread of the end cap 30, and the plug itself is provided with a central bore 15 of relatively small diameter, as shown. The individual plugs 13 extend into the open air space 16 outside of 10 the furnace chamber and are thus exposed to the cooling influence of the air; so that, when the molten lead, or the like, is poured into the individual upright tubes 8 and enters the narrow bore 15 of the plugs, it will 15 tend to chill in said bore so as to solidify therein and prevent the running out of the lead during the operation of filling the individual tubes 8. The promptness with which this chilling takes place is further insured 20 by means of cooling jets 27 supplied from a water supply pipe 32 (see Fig. 4), and in such position with respect to the bored plugs that the jets will direct sprays of cold water or the like upon the bored plugs when desired.

So also, means are provided, as represented, for instance, by the oil jet burner 25 to direct a heating flame on the bored plugs 13, of such a character as to promptly bring the chilled lead therein to fusion when desired. The operator, therefore, is enabled, at will, either to bring the lead within the bored passages of the plugs 13 into fusion or to congeal the lead in said passages.

35 The lower screw-threaded end of each individual plug is connected by a branch pipe 18 with a main supply pipe 19 for the crude oil conveyed to the several tubes 8 of the distilling and cracking unit. In each of 40 these branch pipes is arranged a suitable meter 20 provided with a by-pass 21, and appropriate valves, as indicated at 22, are provided for determining the flow through the meter and by-pass or to cut the one or the 45 other out of the circuit altogether.

The main pipe 24 for conveying the oil to the individual bored plugs of the upright tubes 8 is connected to a superheater of some appropriate kind. As indicated in Figs. 1 and 2, the general structure, for this purpose, includes, in addition to the heating chamber 4, a heating chamber 40 communicating with the common stack 6. This heating chamber 40 is traversed by a pipe system 41 for pre-heating the oil supplied to the pipe 24; and, 50 connected with this system is the pump 42. From each of the individual branch pipes 23, return pipes 26 connect with the return branch 24^a of the main 24, and to this return main there is likewise connected the supply pipe 43 leading from the source of oil storage and which, together with the return branch 24^a connects with the suction side of the pump.

60 In the practice of the invention, when the

several upright tubes 8 have received (up to or nearly up to the header 9) their filling of molten lead, a portion of which is congealed in the bored passages 15 of the plugs 13, a condition of pressure is created in the system, by means of the pump. Thereupon, the water jets having been turned off and the heating flame applied to the several plugs 13, the congealed lead in the bored passages of the individual plugs is brought to 70 fusion. As soon as the lead in the bored passages has been brought to full fusion, the preheated crude oil, by reason of the pressure prevailing in the system is forced upwardly through said passages into the upright tubes 8, and passes into the columns of 75 molten lead contained therein, the pressure employed being sufficient to keep the passages of the several plugs clear of lead. In its upward passage through the columns of 80 lead contained in the upright tubes 8, the crude oil is distilled, with the formation of coke which enters the header 9, and is continuously or intermittently blown by a steam jet or the like 48 into the upright drum 11. 90 At the same time, the distillation of the crude oil is accompanied by its partial or complete desulfurization, according to the character of the molten material employed in the tubes 8. The gaseous or vaporous products of 95 distillation pass into the drum 11 and on into the condenser (not shown) by the pipe 29. By the employment of a suitable loaded valve on either the inlet or the outlet side of the condenser, a back pressure will be 100 produced determining the degree to which the products of distillation are cracked.

It will be understood that, quite aside from any desulfurizing function of the molten lead by chemical combination with the sulfur of the crude oil, the vaporization and gasification incident to the distilling operation themselves effect in part a separation of the sulfur, and, the sulfur or sulfur compounds thus separated are condensed in large part 110 in the drum 11 instead of passing on to the condenser. The desulfurizing of the crude oil is therefore due to the combined action of the lead in the formation of lead-sulfur compounds, to the extent to which such compounds are produced, and to the dissociating effect (upon the sulfur and sulfur compounds contained in the oil,) of the heat of fusion of the lead or other like molten material employed. Either of these effects is, in 115 general, sufficient to reduce the content of sulfur in the ultimate product to the required degree for use as a marine boiler fuel, and their combined effect proportionately reduces the sulfur compound to a still 120 lower percentage.

It will be understood that I do not limit myself to the employment of lead as the filling of the upright tubes, nor to the employment of any like material having a capacity 125 130

to chemically unite with sulfur. Where lead is employed, however, and when, for any reason it is desired to regenerate the lead so as to restore it to its original metal condition, this may be accomplished either in situ by blowing air upward through the lead, after disconnecting the elbow pipe 10 from the drum 11, thus bessemerizing the lead, or by removing the lead from the tubes 8 in any suitable way (as, for instance, by disconnecting the plugs 13) and permitting the contents of the several tubes to flow into an appropriate bessemerizing receptacle and blowing air through the lead thus collected until the sulfur has been driven off to the desired degree.

Whenever it is necessary to interrupt the distilling operation, either for the removal and regeneration of the lead or other molten material, or otherwise, the heating flame is turned off, and the cooling sprays of water are directed upon the bored plugs 13 so as to congeal the lead therein and thereby close the plugs.

In further explanation of the characteristic features of the invention, I desire to point out that the employment of the series of upright tubes 8, constituting with the horizontal header 9, the distilling unit, presents the distinctive advantage of obtaining with a relatively small quantity of the lead or other like molten material an extensive heating surface and practically the maximum travel of oil through the molten material. This insures the complete distillation of the oil to coke, and the corresponding release of the sulfur from the oil, which, as I have already pointed out, is to a very large extent, due to the thermal conditions of the distillation and due entirely thereto when the molten material employed does not combine chemically with the sulfur, which is not always the case even when lead is employed as a molten material. Furthermore, the employment of the upright tube header system characteristic of the invention, has advantage over the employment of lead or the like in an ordinary horizontal cylindrical still for the reason that to suitably protect the heating surface of such a still by means of lead, would require the employment of a quantity of lead so large as to reduce the heating surface to a relatively small percentage or, in the alternative, would create a load in the still so great that the still would be distorted at the temperatures necessary to the distillation process; whereas, in the upright header system of my invention, not only is the amount of lead employed reduced to a low minimum, but the element of still distortion is wholly absent.

So also, the employment of the upright tube header system provides a practical way for carrying on the process continuously for the complete continuous conversion

of the entire body of crude oil into the gaseous or vaporous condition, with the dissociation of the sulfur and with the continuous production of coke, and particularly with the continuous removal of the coke, which, floating to the surface of the molten material of higher specific gravity may be promptly expelled from the header into the receiving drum thereby keeping the distilling apparatus continuously disengaged of its presence.

Furthermore, in the practice of the invention, the employment of the bore or passage of relatively small diameter through which the oil is injected into the upright tubes insures the passage of the oil therethrough with such relative velocity as to exclude the down-passage of the lead during the distilling operation, and nevertheless permits the sealing of the upright tubes by congealing of the lead within these almost capillary passages, as soon as the heating jets are extinguished and the chilling water spray or the like is applied. The operation of the apparatus is so sensitive in this regard that the passages 15 of the plugs will remain securely obstructed by the congealed lead therein until such time as the oil to be distilled reaches the temperature at which it is desired to begin to discharge it into the tubes 8, whereupon, by igniting the heating jets or burners, the lead in the restricted passages 15 will be brought into fusion so promptly that the oil under pressure will immediately clear the passages and will keep them open until the operator desires to shut down; whereupon, a lowering of the pressure on the oil feed, the turning off of the heating jets, and the turning on of the water sprays will, with similar promptness, congeal the lead as it starts down through the passages and securely close them until it is necessary to start up again. This form of control is particularly adapted to the purposes of the invention, inasmuch as it dispenses with the employment of any form of check valve.

In the cracking of oils, for the purposes of increasing their proportion of gasoline, it has heretofore been the uniform practice, insofar as I am aware, to employ as the still charge an oil which is itself the product of distillation. To attempt to subject ordinary crude oil to a cracking operation in such stills would result in the separating out and deposition upon the heating surfaces of such a quantity of dirt and carbonaceous matter as would distort the stills, and, at the high pressures employed would cause their explosion. On the other hand, the employment of the apparatus of the present invention, as a cracking unit for crude oil is entirely feasible, without danger, for the reason that not only the carbonaceous matter, but the dirt as well, is carried to the upper

surface of the lead and is continuously removed, so that it interferes in no wise with the uniformity, regularity, and safety of the operation.

5 As hereinbefore indicated, a striking merit of the invention is its capacity to distill Mexican crude oil to coke continuously, and, nevertheless, to produce a refined product, so low in sulfur that it makes a satisfactory fuel oil for marine boiler firing, fully meeting the naval specifications in that regard. All Mexican crude oil with which I am familiar, contains more than 3% of sulfur and is unsuitable for marine fuel oil, 10 not only on account of its sulfur content, but also on account of its high viscosity. When distilled in accordance with the present invention, the distillate is not only suitable for marine boiler firing, but can be 15 used as a gas oil in the production of illuminating gas, and in oil refineries for the production of lubricating oils, gasolene, kerosene, and paraffin wax. The coke constituting the by-product of the operation 20 may be readily briquetted and sold for fuel purposes, and the diminished weight of the distillate as compared with the original crude oil permits it to be shipped at a diminution in freight rates represented by 25 30 the weight of the coke removed in the distilling process, which frequently amounts to from 18 to 22%. It will, of course, be understood that not only the coke but any solid impurities carried up with it to the surface 35 of the molten material and into the header will likewise be discharged into the receiving drum by the steam jet or its equivalent. It is further to be noted that the receiving drum is to be maintained gas-tight during 40 the distilling operation and capable of withstanding whatever back pressure is set up in the system to produce the cracking effect desired.

Referring further to the desulfurizing of 45 the lead, when such desulfurizing is required, it is preferred to carry it out in situ i.e., without removing the lead from the upright tubes 8. To this end, the heavy oil should be removed from the system by 50 pumping in distillate until all of the heavy oil is displaced. Thereupon the distillate and the oil vapors are blown out of the entire system by steam. The pipe 10 is then put into communication with the atmosphere, and air is blown in through the bored 55 passages of the injector plugs until the lead is appropriately desulfurized. Finally, the air is, in its turn, driven out by steam, whereupon the distillation of the crude oil 60 may be resumed.

It will, of course, be understood that any fixed gases produced as an incident to the distilling and cracking operation, and also any gaseous sulfur compounds produced, 65 will pass on from the vertical drum into the

pipe leading to the condenser for the distillate and may be removed either before or after passing through the condenser.

Having thus described my invention, what I claim is:

70

1. Apparatus for the refining of petroleum, comprising a series of upright tubes, said tubes being provided with a filling of molten material, injectors of relatively small bore forming extensions of the tubes, said injectors discharging petroleum into the lower ends of the tubes, against the pressure of the molten material, and means for bringing into fusion any of the molten material that has congealed in the injectors; substantially as described. 75 80

2. Apparatus for the refining of petroleum, comprising a series of upright tubes, said tubes being provided with a filling of molten material, injectors for the petroleum, said injectors discharging into the lower ends of the tubes and forming a continuation thereof of relatively small bore, means for congealing that part of the molten material that finds its way into the injectors, means for re-melting the congealed material, and means for creating a petroleum pressure in the system back of the several injectors so that on said re-melting of the petroleum will immediately rush into the injectors and on into the main body of molten material above; substantially as described. 85 90 95

3. Apparatus for the refining of petroleum, comprising a series of upright tubes, said tubes being provided with a filling of molten material, injectors for the petroleum, said injectors discharging into the lower ends of the tubes and forming a continuation thereof of relatively small bore, means for congealing that part of the molten material that finds its way into the injectors, means for re-melting the congealed material, and means for creating a petroleum pressure in the system back of the several injectors so that on said re-melting the petroleum will immediately rush into the injectors and on into the main body of molten material above, said pressure means consisting of a pump having a discharge main and a return main, the latter being also connected with the source of petroleum supply, and the several injectors being connected up by branch piping in parallel across the said discharge and return mains; substantially as described. 100 105 110 115

4. Apparatus for the refining of petroleum, comprising a series of upright tubes, said tubes being provided with a filling of molten material, injectors for the petroleum, said injectors discharging into the lower ends of the tubes and forming a continuation thereof of relatively small bore, means for congealing that part of the molten material that finds its way into the injectors, means for re-melting the congealed material, and means for creating a petroleum 120 125 130

pressure in the system back of the several pipe, and the several injectors being connected so that on said re-melting the said up by branch piping in parallel across the petroleum will immediately rush into the said discharge and return means, and said injectors and on into the main body of branch piping being provided with meters 5 molten material above, said pressure means, and by-passes; substantially as described. consisting of a pump having a discharge In testimony whereof I affix my signature. main and a return main, the latter being also connected with the source of petroleum sup-

JOHN LATHROP GRAY.
